FEEDING MECHANISM

Filed Dec. 21, 1922

UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

FEEDING MECHANISM.

Application filed December 21, 1922. Serial No. 608,803.

My invention relates to feeding mechanisms, and more particularly to feeding mechanisms for rock drilling devices.

An object of my invention is to provide an improved feeding mechanism. Another object of my invention is to provide an improved fluid pressure operated feeding mechanism having improved controlling means. A further object of my invention is to provide an improved feeding mechanism of the stopper type having improved means for controlling the operation thereof. Still another object of my invention is to provide improved controlling means for the feeding means of a rock drilling mechanism which is automatically controlled by the varying resistance to rotation of the drilling tool. Other objects and advantages of my invention will herein-after more fully appear.

20 In the accompanying drawings I have shown for purposes of illustration one form which my invention may assume in practice.

In these drawings,—

Fig. 1 is a view, partially in elevation and 25 partially in central longitudinal section through a drilling mechanism in which the illustrative form of my invention is incorporated.

Fig. 2 is an enlarged view, partially in elevation and partially in central longitudinal section, showing the details of construction of the feeding mechanism.

Fig. 3 is a view in transverse section on the line 3—3 of Fig. 2.

35 Fig. 4 is an elevation of the brake applying band which I employ.

Fig. 5 is a transverse horizontal sectional view taken substantially on line 5—5 of Fig. 1.

In this illustrative form of my invention 40 I have shown it employed in a stoping mechanism generally designated 1 and comprising a drilling motor 2 in whose cylinder 3 a piston 4 reciprocates, the piston 4 being operative in its reciprocation to rotate, by usual ratchet 45 and pawl mechanism whose casing is generally designated 5, and to strike a drill steel 6. As shown the piston 4 is provided with a forwardly projecting striking bar 4^a having formed thereon spiral and straight grooves 5^a which cooperate respectively with a pawl carrier 6^a and a usual chuck nut 7^a, the latter being threadedly secured within a usual rotatable chuck member 8^a which receives the drill steel 6. Herein the pawl carrier 6^a has 55 a plurality of spring pressed pawls 9^a mount-

ed thereon which are adapted to react on a relatively stationary internal ratchet ring 10^a.

Feeding means for feeding the drilling mechanism toward the work is provided and comprises a feed cylinder 7 in which a feed piston 8 is reciprocable, the latter having a piston rod 9 which is provided with a plurality of key-ways 10 whose function will herein-after be explained. At its rear end the piston rod 9 has pivotally connected thereto a foot piece 11 which is provided with a plurality of relatively sharp blades or toes 12 which are adapted to be pressed tightly against an extraneous abutment during drilling and prevent rotation of the feed piston rod. Secured to the rear end of the cylinder 7 is a housing generally designated 15 comprising two elements; a member 16 threaded into the rear end of the cylinder 7 and a closure member 17. Within the members 16 and 17 there is formed 75 a chamber surrounding the piston rod and in this chamber next to the rod is arranged a split brake material receiving sleeve of relatively thin metal 18 in which a band of brake material 19 is carried. Surrounding the sleeve 18 is a resilient brake applying band of generally helical form 20 having at its opposite ends enlarged portions or lugs 21 and 22. The lug 21 of the band is adapted to be seated in a groove 23 formed in the interior of the member 16 and a means, as indicated at 24, is provided for preventing relative rotation 80 between the cylinder and the member 16 thus causing the lug 21 to move relative to the stationary piston rod, this being true either during longitudinal movement or rotative movement of the cylinder member 7. Surrounding the piston rod below the member 22 and at the rear end of the chamber formed between the members 16, 17 and the piston rod 9 is a 85 sleeve member or collar 25, this sleeve member being splined and cooperating by means of its splines with the grooves 10 previously described, whereby no rotation of the sleeve or collar 25 can occur without rotation of the piston rod. The member 25 is also provided with a notch or groove 26 in which the lug 22 is located. From the construction described, it will be apparent that relative rotation between the cylinder 7 and piston rod 9 100 will be accompanied by tightening or loosening of the band 20 and so by application or release of the brake, due to the varying resistance to drill steel rotation. A handle member 27 is provided for the purpose of enabling 105 110

the drill runner to conveniently hold the drill at certain times during operation and for the purpose of bodily turning the motor and feed cylinder enabling him to control the brake as will hereinafter appear.

The mode of operation of my invention will be clearly apparent. Let it be assumed that the drilling apparatus is set up in position to start a hole with the foot piece 11 engaging an abutment and with the feed partially extended and with the drill steel against the rock. The operator by preventing rotation of the member 11, as he can do by placing his foot upon it, and by turning the cylinder 7 relative to the piston rod 9, as may be done by pulling or pushing, depending upon the construction, upon the handle 27, may retard the feed as much as desired, the release of the handle 27 or moving of it in what might be called its backward direction, releasing the feed entirely or partially, depending upon the degree of movement. After the hole is started, it will always be possible to vary the feed simply by placing a tension upon the brake band through pulling upon the handle 27 although the handle is normally released at this time. Moreover, should the drill steel stick or jam, or should muddy or sticky drilling be encountered so that the rotation was materially more difficult, it will be evident that the feed would be retarded by the reaction, through the ratchet and pawl mechanism the motor and feed cylinder, of the rotation mechanism upon the band 20 acting on the stationary piston rod, any increased resistance to rotation tending with a member 20 whose helix is wound in the right direction to cut down the rate of feed and so to render the drill automatically self-controlling as to the strength of feed. It will of course be understood that this operation will result regardless of the type of steel rotating mechanism used and that it is my intention herein to cover my improvement in connection with any such rotating mechanism.

While I have in this application specifically described one form which my invention may assume in practice, it will be understood that this form of the same is shown for purposes of illustration and that the invention may be modified and embodied in various other forms without departing from its spirit or the scope of the appended claims.

55 What I claim as new and desire to secure by Letters Patent is:

1. In a drilling mechanism, the combination with means for rotating the drill steel and means for feeding the steel including relatively rotatable feeding elements, of feed controlling means responsive to the resistance to drill steel rotation and operative upon relative rotation between said feeding elements for automatically restraining movement between said feeding elements.

2. In a drilling mechanism, the combination with means for rotating the drill steel and means for feeding the steel including relatively rotatable feeding elements, of feed controlling means responsive to the resistance to drill steel rotation and operative upon relative rotation between said feeding elements for automatically applying friction between said feeding elements. 70

3. In a drilling mechanism, the combination with means for rotating the drill steel and means for feeding the steel comprising a pair of telescoping feeding members having relative longitudinal movement during feeding, of feed control means responsive to the resistance to drill steel rotation for automatically variably applying friction between said members, said automatic means including frictional resistance means directly frictionally engaging one of said feeding members. 75 80 85

4. In a drilling mechanism, the combination with means for rotating the drill steel and feeding means for the steel comprising a stationary feeding member having means for preventing rotation thereof during drill feed and a rotatable and longitudinally movable feeding member, of means responsive to the resistance to drill steel rotation for automatically controlling said feeding means. 90

5. In a drilling mechanism, the combination with means for rotating the drill steel and feeding means for the steel comprising a stationary feeding member and a rotatable and longitudinally movable feeding member, of feed controlling means responsive to the resistance to drill steel rotation for automatically restraining movement between said feeding members. 95 100 105

6. In a drilling mechanism, the combination with means for rotating the drill steel and feeding means for the steel comprising relatively rotatable and relatively longitudinally movable feeding members, of means responsive to the resistance to drill steel rotation and rendered effective through relative rotation of said members for automatically controlling said feeding means. 110 115 120

7. In a drilling mechanism, the combination with means for rotating the drill steel and feeding means for the steel including relatively rotatable and relatively longitudinally movable feeding elements, of means responsive to the resistance to drill steel rotation and operative upon relative rotation between said feeding elements for automatically controlling said feeding means, and manually operable means cooperating with said automatic means for controlling said feeding means. 125

8. In a drilling mechanism, the combination with means for rotating the drill steel and feeding means for the steel including relatively movable feeding elements, of means operatively connected to said feeding elements and responsive to the resistance to drill 130

steel rotation for automatically controlling said feeding means, said means including a resilient friction band adapted to be contracted and expanded as the resistance to drill steel rotation varies.

9. In a drilling mechanism, the combination with means for rotating the drill steel and feeding means for the steel including relatively movable feeding members, of means responsive to the resistance to drill steel rotation for automatically controlling said feeding means, said means operatively connected to said feeding members and including a resilient friction band engageable with one of said feeding members and adapted to be contracted and expanded as the resistance to drill steel rotation varies.

10. In a drilling mechanism, the combination with a motor for rotating the drill steel and feeding means for the steel including relatively movable feeding members, one of which is stationary, of means responsive to the resistance to drill steel rotation and operative only upon relative movement between said feeding members for automatically applying resistance between said feeding members to control the rate of feed.

11. In a drilling mechanism, a drilling motor, feeding means therefor, including a normally stationary feeding element, a brake for controlling said feeding means, and manually operable means for bodily rotating said motor relative to said stationary feeding element for applying said brake.

12. In a drilling mechanism, a drilling motor, feeding means therefor including relatively movable members, a brake for controlling said feeding means, and manually operable means comprising a grasping handle projecting laterally from the drilling mechanism for positively moving one of said members angularly relative to the other member for applying said brake.

13. In a drilling mechanism, a drilling motor, feeding means therefor, a brake for controlling said feeding means, and means including a manually graspable handle projecting from the drill for enabling the operator to bodily rotate the drilling motor to control said brake.

14. In a drilling mechanism, a drilling motor, means for rotating a drill steel, feeding means for said drilling motor comprising a stationary non-rotatable member, a rotatable and longitudinally movable member connected to the drilling motor, and means controlled by rotary movement of said rotatable feeding member effected by the varying resistance to rotary movement of said drill steel adapted to automatically restrain said feeding means.

15. In a drilling mechanism, a drilling motor, a supporting handle carried thereby and rigidly fixed against movement relative thereto, feeding means for said drilling motor, and means operated by the rotation of said handle

adapted to restrain said feeding means mechanically.

16. In a drilling mechanism, a drill motor, a supporting handle carried thereby, and rigidly fixed against movement relative thereto, feeding means for said drilling motor, and means operative by the rotation of said handle about the axis of said drilling motor to restrain said feeding means.

17. In a drilling mechanism, a drilling motor, feeding means therefor comprising a normally stationary non-rotatable member and a rotatably movable member, and means carried by said movable member and controlled by the rotation thereof adapted relative to said stationary feeding member to resist feeding movement.

18. In a drilling mechanism, a drilling motor, feeding means therefor comprising a feed cylinder element and piston element, said elements being relatively rotatable, and automatic means carried by said feed cylinder and controlled by the relative rotation between said elements adapted to apply friction to said piston element.

19. In a drilling mechanism, a drilling motor, feeding means therefor including a normally stationary feeding element, said drilling motor being bodily rotatable relative to said stationary feeding element, a brake, and means controlled by the rotation of said drilling motor relative to said stationary feeding element for applying said brake to retard said feeding means.

20. In a drilling mechanism, a drilling motor comprising a cylinder and a piston reciprocable therein, a drill steel adapted to receive blows from said piston, rotation means for the drill steel operated by said piston, feeding means for said motor including relatively movable feeding elements one of which is stationary, and feed control means carried by the movable feeding element and automatically controlled by the resistance to rotation of said drill steel to apply friction directly to said stationary element of said feeding means.

21. In a drilling mechanism, a drilling motor adapted to transmit blows to a drill steel, drill steel rotating means operated thereby, feeding means including relatively movable feeding elements, a brake, and means automatically controlled by the resistance to drill steel rotation adapted to apply said brake to one of the feeding elements to retard said feeding means, said brake being mechanically applied and released wholly without manual intervention as the resistance to drill steel rotation varies.

22. In a drilling mechanism, a drilling motor, feeding means therefor comprising a feed cylinder and piston, said cylinder being rotatable relative to said piston, means for resisting rotation of said cylinder relative to said piston, and friction means car-

- ried by said feed cylinder and automatically controlled by the resistance to rotation thereof adapted to retard relative movement between said cylinder and piston.
23. In a drilling mechanism, a drilling motor, feeding means therefor including relatively rotatable feeding elements, a brake for controlling said feeding means, and combined automatic and manual means adapted to brake said feeding means upon rotation of one of said feeding elements relative to the other, and means for effecting rotation of one of said feeding elements relative to the other.
24. In a drilling mechanism, a drilling motor including steel rotating means, air pressure feeding means therefor, and automatic means controlled by the rotation of said steel rotating means adapted to restrain said air pressure feeding means, said automatic means comprising a mechanically operated brake automatically applied and released wholly without manual intervention as the resistance to drill steel rotation varies.
25. In a drilling mechanism, a drilling motor for actuating a drill steel, feeding means therefor including feeding elements having relative angular and longitudinal movements, rotation means for said drill steel, and frictional resistance means automatically mechanically operative to control the operation of said feeding means in accordance with the nature of the drilling encountered by the drill steel, said automatic means being mechanically applied and released automatically as the resistance to drill steel rotation varies.
26. In a drilling mechanism, a drilling motor and feeding means therefor comprising a cylinder and piston, one of which is connected to said motor and the other of which non-rotatively engages an abutment, a housing fixed relative to said cylinder member, a brake in said housing, and brake applying means including a band one end of which is fixed to said housing and whose other end is fixed against rotation with respect to said piston member, and means including a collar non-rotatively connected to said piston member but between which and said piston member relative longitudinal movement occurs during feeding, said collar receiving the last mentioned end of said band.
27. In a drilling mechanism, in combination, a drilling motor and feeding means therefor comprising a cylinder and piston, one of which is attached to said motor and the other of which non-rotatively engages an abutment, and means for frictionally controlling movement between said cylinder and piston including a brake, and a brake applying member whose opposite ends are respectively connected to said cylinder and piston members, said brake applying member engaging said brake for applying or releasing the same.
28. In combination, a drilling motor, feeding mechanism therefor including a longitudinally and angularly movable cylinder connected to said motor, a piston having a rod non-rotatively engaging an abutment, and means for controlling said feeding mechanism including a brake carried by said cylinder and engaging said piston rod, and brake applying means including a band member whose opposite ends are respectively fixed as to angular movement with respect to said cylinder and piston, said brake applying means being operative to apply said brake upon angular movement of said feed cylinder relative to said piston.
29. In a drilling mechanism, a drilling motor, feeding means therefor including relatively rotatable members, and means for controlling said feeding means operative upon relative rotation between said feeding members and including an element splined in longitudinal sliding relation with one of said members and a braking element cooperating respectively with said element and one of said members.
30. In a drilling mechanism, a drilling motor, feeding means including relatively angularly movable feeding members, and means for controlling said feeding means including a friction device operative upon relative angular movement between said feeding members.
31. In a drilling mechanism, the combination with means for actuating the drill steel and feeding means for the steel comprising relatively angularly and relatively longitudinally movable feeding members, of means automatically operative upon relative angular movement between said feeding members for controlling said feeding means in accordance with the nature of the work encountered.

In testimony whereof I affix my signature.

CHARLES F. OSGOOD.

CERTIFICATE OF CORRECTION.

Patent No. 1,690,429.

Granted November 6, 1928, to

CHARLES F. OSGOOD.

It is hereby certified that error appears in the printed specification of the above numbered patent requiring correction as follows: Page 2, line 33, after the word "mechanism" insert a comma; page 3, line 21, claim 10, after the word "members" strike out the comma; line 29, claim 11, after the word "therefor" strike out the comma; and line 69, claim 16, after the word "thereby" strike out the comma; line 80, claim 17, strike out the word "adapted" and insert the same to follow after the word "member" in line 81; and that the said Letters Patent should be read with these corrections therein that the same may conform to the record of the case in the Patent Office.

Signed and sealed this 11th day of December, A. D. 1928.

(Seal)

**M. J. Moore,
Acting Commissioner of Patents.**
